W. BAYLOR

BIN

Filed May. 31, 1922

Inventor

W. Baylor

By *Watson E. Coleman*
Attorney

UNITED STATES PATENT OFFICE.

WILLIAM BAYLOR, OF LESTER MANOR, VIRGINIA.

BIN.

Application filed May 31, 1922. Serial No. 564,982.

To all whom it may concern:

Be it known that WILLIAM BAYLOR, a citizen of the United States, residing at Lester Manor, in the county of King William 5 and State of Virginia, has invented certain new and useful Improvements in Bins, of which the following is a specification, reference being had to the accompanying drawings.

10 This invention relates to certain improvements in bins and it is an object of the invention to provide a device of this general character having novel and improved means whereby rodents which enter the bin may 15 be readily and effectively trapped.

Another object of the invention is to provide a device of this general character embodying a false bottom provided with openings whereby a rodent entering within the 20 bin may have convenient access to a supplemental compartment between the main and false bottoms of the bin together with means working within the compartment to facilitate the trapping of the rodent therein or the 25 removal of such rodent therefrom.

The invention consists in the details of construction and in the combination and arrangement of the several parts of my improved bin whereby certain important advantages are attained and the device rendered simpler, less expensive and otherwise 30 more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:

40 Figure 1 is a view in elevation illustrating a bin constructed in accordance with an embodiment of my invention;

Figure 2 is an enlarged transverse sectional view taken through the device as 45 shown in Figure 1;

Figure 3 is an enlarged vertical sectional view taken longitudinally of my improved bin; and

Figure 4 is an enlarged fragmentary sectional view taken substantially on the line 50 4—4 of Figure 1.

As disclosed in the accompanying drawings, my improved bin comprises imperforate end members 1 of requisite dimensions 55 and which are connected adjacent their

lower ends by a bottom 2. Also connecting the end members 1 and spaced above the bottom 2 is a horizontally disposed partition or false bottom 3. This partition or bottom 3 is provided with a plurality of openings 4 to permit entry within the compartment 5 between the bottoms 2 and 3. 6 denotes the sides of the bin which are preferably formed of screen sheets or other foraminated material. T denotes a top of the bin which also 65 preferably comprises a foraminated portion 7. The top T may be hingedly connected as at 8 for swinging movement or otherwise constructed as the requirements of practice may necessitate.

70 One of the side walls 6 is provided with the openings 9 to provide an entrance for rodents, said openings being positioned in relatively close proximity to the partition or false bottom 3. Each of these openings 9 is 75 defined by an inwardly directed entrance tube or chute 10 preferably formed of reticulated material and herein disclosed as frusto-conical with the smaller end inwardly disposed. These tubes or chutes 10 80 offer no undue hindrance of obstruction to the entrance of a rodent within the bin but serve effectively to prevent a rodent escaping therethrough. My improved bin is adapted to contain dry groceries in packages 85 such as flour, rice, oatmeal and the like and which is particularly subjected to attack by rodents. A rodent entering the bin through either of the openings 9 is prevented from escape through such openings by the tubes 90 or chutes 10. When the rodent is alarmed as by a person coming to the bin to take out a package therein the natural characteristic of said rodent will cause him to endeavor to escape by passing through an opening 4 into 95 the chamber 5. This chamber 5 may have placed therein poison bait to effect the extermination of the rodent or if preferred the rodent within the chamber 5 may be further trapped while alive.

100 Loosely arranged within the chamber 5 is an elongated member 11 of a length substantially equal to the width of the bin and of a height to substantially bridge the space between the bottoms 2 and 3. Secured, 105 as at 12, to the opposite faces of the member 11 are the flexible members 14. These members 14 are disposed in opposite directions and are freely directed through the openings 15 in the end members 1 of the bin.

The member 11 is initially positioned in substantially close contact with an end member 1 of the bin as is particularly illustrated in Figure 1 and after a rodent has entered 5 the compartment 5 one of the members 14 is pulled to cause the member 11 to travel toward the opposed end member 1 resulting in the rodent being effectively trapped and held between said member 11 and the second 10 end member of the bin. With the rodent held in such position the door 16 is moved into open position to effect the desired removal of the rodent from within the compartment 5 and which removal can 15 be effected when the rodent is alive or when life is extinct from the result of poison. The member 11 may be also caused to strike the rodent with sufficient impact to kill the same and particularly 20 by forcing the rodent against the end member 1 of the bin adjacent to which is arranged the door 16. The door 16 is as herein disclosed is of a sliding type although I do not wish to be understood as limiting 25 myself in this respect.

In order to close the openings 9 to prevent ingress therethrough of a rodent the same are closed by an elongated flat strip 17 which has each end portion pivotally 30 connected as at 18 with an end member 1. The strip 17 has swinging movement in a vertical direction and is of such a width to overlie or close the openings 9 when said strip is swung upward toward the adjacent 35 side wall 6. When the strip 17 is extended as is illustrated in Figure 2 of the accompanying drawings it provided a platform

to facilitate the passage of a rodent through an entrance opening 9.

From the foregoing description it is 40 though to be obvious that a bin constructed in accordance with my invention is particularly well adapted for use by reason of the convenience and facility with which it may be assembled and operated, and it will also 45 be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In combination with a bin, a false bottom arranged therein and spaced from the main bottom of the bin to provide a compartment, said false bottom being provided with an opening to provide an entrance within the 60 compartment, a movable member within the compartment, said member extending substantially entirely across the compartment and bridging the space between the top and bottom thereof, flexible members secured to the first named member and extending exteriorly of the bin through the opposite ends thereof, said members providing means whereby the first named member may move in either direction lengthwise of the compartment.

In testimony whereof I hereunto affix my signature.

WILLIAM BAYLOR.
